(57) **CLAIM**

The ornamental design for a carrying case for blood glucose meter and diabetic testing supplies, as shown and described.

DESCRIPTION

The FIGURE is a front view of a carrying case for blood glucose meter and diabetic testing supplies, shown in an open state displaying the interior of the article with two-dimensional ornamental design elements formed on inner surfaces of the article.

Described is a new, original, and ornamental design for a carrying case for blood glucose meter and diabetic testing supplies, for of which the following is a specification, reference being had to the accompanying drawings forming a part hereof. The claimed carrying case for blood glucose meter and diabetic testing supplies includes ornamental features of a carrying case that securely stores a blood glucose meter and diabetic testing supplies including disinfectant alcohol pads, test strips, a lancing device, batteries, a spare lancet drum or vial of control solution, and that provides a receptacle to receive used test strips. The claimed ornamental design includes only the text, garbage can, and arrow symbol, each of which is depicted as a two-dimensional element in solid lines, in the FIGURE.
